Attorney

UNITED STATES PATENT OFFICE.

THOMAS SEZABURO MATSUOKA, OF ARROW, COLORADO.

TIE-PLATE.

1,240,865.

Specification of Letters Patent. Patented Sept. 25, 1917.

Application filed May 23, 1916. Serial No. 99,330.

To all whom it may concern:

Be it known that I, THOMAS SEZABURO MATSUOKA, a citizen of the United States, and resident of Arrow, in the county of 5 Grand and State of Colorado, have invented certain new and useful Improvements in Tie-Plates, of which the following is a specification.

The present invention relates to new and 10 useful improvements in railway road-bed appliances and has particular reference to a new and improved tie-plate for supporting railway rails on wooden ties or the like.

The primary object of my invention is 15 to provide a tie-plate of the class described having means for reinforcing the rail holding element, which in the present instance would be the usual spike, means for preventing lateral displacement of the rail, and 20 means for preventing skidding of the tie-plate on the tie.

Another object of my invention is to provide a tie-plate of the class described formed from a single casting with the element mentioned in the foregoing associated therewith whereby to reduce the cost of manufacture of such devices without materially reducing their effectiveness.

Other objects and advantages to be derived from the use of my invention will appear from the following detail description and the claim, taken with an inspection of the accompanying drawing, in which:—

Figure 1 is a perspective view of a rail 35 and tie showing my improved tie-plate applied in operative position;

Fig. 2 is a top plan view of the same; and Fig. 3 is a bottom plan view of the same.

Referring more particularly to the drawing, wherein similar characters of reference designate like and corresponding parts throughout the various views, 1 designates the body portion of my invention which is 40 rectangular in configuration in the preferred form of the device. The intermediate portion of the plate 1 receives a rail, a plurality of intersecting grooves 2 being diagonally arranged on the upper face of said plate to permit moisture to drain between 45 the rail and the plate.

The upper face of the plate 1 is also provided with reinforcing elements, said reinforcing elements being formed of lugs 3 having vertical walls thereof arranged adjacent apertures 4 formed in said plate. 50 These lugs 3 serve to reinforce the rail hold-

ing elements which in the present instance are the usual spikes 5, best shown in Fig. 1. An intermediate reinforcing lug 6 is provided having the vertical end wall thereof 60 engaging a rail. It will be seen that in the provision of the lug 6 I afford means for preventing spreading of the rails, one of the most predominant causes of wrecks on railways at the present time, this lug 6 being 65 found particularly useful when used in connection with the outside rail on a curve. A second pair of apertures 7 are provided in the plate 1, said apertures being arranged at a distance from the apertures 4 and being 70 adapted to receive spikes or similar fastening elements.

The under side of the plate 1 is provided with a plurality of intersecting diagonally arranged ribs 8 and 9, there being sets of 75 each at each end forming a chamber 10 approximately centrally of the under face of the plate whereby to form means for preventing lateral or longitudinal displacement of the plate on the tie. It will be obvious 80 that when the spikes are driven home the chamber 10 forms a suction on the tie assisting in maintaining the plate against displacement. In Fig. 1 I have shown a railway rail 11 of the usual formation and a 85 tie 12. In the present instance the tie is formed of wood, but, of course, it will be understood that various materials may be substituted therefor. A pair of flanges 13 and 14 extend along the longitudinal marginal edges of the plate 1 and extend downwardly from the under face thereof, said flanges assisting in preventing lateral displacement of the tie plate.

In the use of my improved tie plate it will 95 be seen that not only are the retaining elements, such as the spikes 5, prevented from distortion under strain, but the rail itself is prevented from being laterally moved, ordinarily termed "spreading." In manufacturing my device the cost will not be materially increased over the cost of the tie-plate now in use, but the effectiveness of the device is materially increased. It will be readily apparent that no moisture can permanently collect between the rail and the tie owing to capillary action, which in the present instance is prevented by means of the drain 2.

From the above description taken in connection with the accompanying drawing, it is thought that a clear and comprehensive

understanding of the construction, operation and advantages of my invention may be had, and while I have shown and described my invention as embodying a specific structure, I desire that it be understood that I may make such changes in said structure as do not depart from the spirit and scope of the invention as claimed.

Having thus fully described my invention, what I claim as new and desire to secure by Letters Patent, is:—

The combination in a tie plate of the class described, of a body portion having a pair of openings on each side thereof, lugs 15 formed on the said body portion adjacent the rear edges of the openings on the upper

face thereof, a reinforcing lug formed intermediate the said lugs for engagement with a rail, the said body portion being provided with a pair of intersecting recesses terminating at a point adjacent the outer edge of the rail to provide means for drainage, flanges formed along the longitudinal edges of the underside of the body portion, a plurality of intersecting diagonally arranged ribs on the said under side, and suction chambers formed by the intersecting of the said ribs to prevent displacement of the plate on the tie.

In testimony whereof, I affix my signature hereto.

THOMAS SEZABURO MATSUOKA.
